UNITED STATES PATENT OFFICE.

JOHN RHODES, OF SEATTLE, WASHINGTON, ASSIGNOR OF ONE-HALF TO HARRY H. CLARK, OF SEATTLE, WASHINGTON.

OIL-BURNER.

1,382,239.

Specification of Letters Patent. Patented June 21, 1921.

Application filed September 20, 1920. Serial No. 411,436.

To all whom it may concern:

Be it known that I, JOHN RHODES, a citizen of the United States, residing at Seattle, in the county of King and State of Washington, have invented a certain new and useful Improvement in Oil-Burners, of which the following is a specification.

My invention relates to improvements in oil burners of the type that are adapted to burn hydro-carbon oils, as kerosene, and the object of my invention is to provide a burner embodying novel means of pre-heating the fuel oil prior to the latter entering the burner conduit.

Another object is to provide an oil burner embodying means to deflect the intense heat away from the burner conduit, thus preventing the same from becoming overheated and carbonized, while still furnishing sufficient heat radiation to sustain and maintain adequate gasification of the fuel within the said conduit until it reaches the combustion aperture.

A further object is to provide an oil burner which is inexpensive and simple in its plan of construction, efficient and reliable in its operation, and which is easily cleaned and will not readily get out of order.

With the above and other objects in view which will appear as the description proceeds the invention consists of the novel construction, adaptation, arrangement and combination of parts hereinafter described and claimed.

I accomplish these objects by devices illustrated in the accompanying drawings, wherein—

Figure 1 is a top plan view of an oil burner embodying the features of my invention.

Fig. 2 is a view in medial vertical section of the same.

Referring to the drawings, through which like reference numerals designate like parts, the numeral 10 designates a fuel supply pipe communicating with a fuel vaporizing chamber 11. Said chamber is preferably formed substantially as illustrated in the drawings and is provided with an integral concave top wall 12. A plug 13 is threadably secured through the side wall of said chamber and serves the double purpose as a supporting means for said burner and as a means of closing a cleanout part 14 provided in said wall.

A burner conduit 15 is threadably secured through the side wall of said chamber diametrically opposite the said plug 13 and in conjunction therewith serves as a supporting means for the burner. The said burner conduit is preferably formed of a single piece of pipe and comprises an outwardly extending portion 15, an upwardly extending portion 16, a diametrically horizontal portion 17, and a downwardly disposed portion 18, all of which portions are substantially in the same central vertical plane. The end of the said burner conduit is provided with a cap 19. A combustion aperture 20 is provided in the under side of the horizontal portion 17 of the said burner conduit, vertically above the center of the top wall 12 of the said chamber 11.

The operation of my device is as follows.

The burner is placed in the fire box of a stove with the plug 13 and outwardly projecting portion 15 of the burner conduit resting in suitable bearings. Fuel oil is introduced through the fuel supply pipe 10 either by gravity or under pressure. After a small quantity of oil has accumulated in the bowl of the concave top wall 12 same is ignited. The oil within the vaporizing chamber 11 will become gasified and rise in the burner conduit. When sufficient gasification has taken place the burner is lighted at the combustion aperture 20.

The flame from the combustion aperture will furnish enough heat when concentrated by the concave construction of the top wall 12 to effect sufficient gasification of the oil within the chamber 11 to supply the burner conduit with a continual supply of vaporized fuel.

By experimental knowledge the burner conduit is offset and at sufficient distance away from the vaporizing chamber 11 to prevent said conduit from becoming overheated and deteriorated by the radiation of heat from the bowl of the concave top wall 12, and, at the same time, is in proper relation with said bowl to insure constant and continual gasification of the fuel in its passage through said burner conduit.

The downwardly disposed portion 18 of the burner conduit serves as a trap to catch residual impurities that fail to gasify. The said portion may be readily cleaned by removing the cap 19.

From the foregoing description taken in

connection with the accompanying drawings, the advantages of the construction and of the method of operation of my oil burner will be readily apparent to those skilled in the art to which the invention relates, and while I have described the principle of operation of the invention, together with the device which I now consider to be the best embodiment thereof, I desire to have it understood that the device shown is merely illustrative and that such changes may be made when desired as are within the scope of the invention.

What I claim is:—

An oil burner comprising a vaporizing chamber, the said chamber having a concave recess formed in the outer top wall thereof, a fuel supply pipe communicating with the said chamber, a plug threadedly disposed in the side wall of the said chamber, a burner conduit threadedly disposed in the side wall of the said chamber diametrically opposite

the said plug, the said plug and the lower end of the said burner conduit being cooperatively adapted to serve as supports for the said oil burner, the said burner conduit comprising an outwardly extending portion, an upwardly extending portion, a diametrically horizontal portion, and a downwardly disposed portion, all of the said portions being in a diametrically central vertical plane relative to the said vaporizing chamber, the said horizontal portion having a downwardly directed combustion aperture formed on the under side thereof disposed concentrically above the said concave recess and a removable cap threadedly secured to the outer end of the said burner conduit.

In witness whereof, I hereunto subscribe my name this 10th day of September, A. D. 1920.

JOHN RHODES.
